[57] **CLAIM**

The ornamental design for a housing panel for electronic equipment, as shown and described.

DESCRIPTION

FIG. 1 is a top, front, right side perspective view of a housing panel for electronic equipment showing my new design;

FIG. 2 is a front view thereof; and,

FIG. 3 is a bottom view thereof.

The top, left side, right side, and back of the housing panel for electronic equipment of my design are unornamented.

The broken line showing on FIGS. 1-3 is for illustrative purposes only and forms no part of the claimed design.

1 Claim, 2 Drawing Sheets

FIG. 3
